COMBINED ESCALATORS AND STREET CROSSING UNIT

Byron B. Savage, Oklahoma City, Okla.

Application January 3, 1956, Serial No. 39,561

Term of patent 14 years

(Cl. D13—1)

The figure is a perspective view of a combined escalators and street crossing unit embodying my new design. The four escalators on the rear side, not fully shown, are similar to those shown on the front side. The dotted lines shown in the drawing are for illustrative purposes only.

I claim:

The ornamental design for a combined escalators and street crossing unit, as shown and described.
